UNITED STATES PATENT OFFICE

92,439

DESIGN FOR A COMFORTABLE OR SIMILAR ARTICLE

Harry O. Sumergrade, New York, N. Y.

Application April 17, 1934, Serial No. 51,427

Term of patent 3½ years

To whom it may concern:

Be it known that I, HARRY O. SUMERGRADE, a citizen of the United States of America, and resident of the city of New York, county of New York, and State of New York, have invented a new, original, and ornamental Design for a Comfortable or Similar Article, of which the following is a specification, reference being had to the accompanying drawing forming part thereof.

Figure 1 is a top plan view of a comfortable or similar article embodying my design; and

Fig. 2 is an enlarged detail view of a portion of the center of my design.

I claim:

The ornamental design for a comfortable or similar article, as shown.

HARRY O. SUMERGRADE.
